CATALYTIC CONVERSION PROCESS

Thomas B. McCulloch, Baytown, Tex., assignor to
Standard Oil Development Company, a corpora-
tion of Delaware

Application October 15, 1943, Serial No. 506,327

9 Claims. (Cl. 260—683.4)

1

The present invention relates to a method for changing the structural configuration of a paraffin hydrocarbon. More particularly the invention is concerned with the isomerization of paraffin hydrocarbons and the utilization of the resulting isoparaffin hydrocarbons in the alkylation of olefins. In its more specific aspects the invention is concerned with the isomerization of normal paraffins to isoparaffins in the presence of sulfuric acid at elevated temperatures followed by the alkylation of the isomerized product with olefins, in the presence of the catalyst withdrawn from the isomerization reaction.

It is well known in the prior art to isomerize normal paraffins to isoparaffins utilizing an aluminum halide in the presence of a hydrogen halide as the catalyst. It is also known to isomerize isoparaffins in the presence of aluminum halides and hydrogen halides and then to utilize the catalyst from the isomerization stage to alkylate the isomerized product with olefins in an alkylation stage. This latter process, however, has disadvantages in that aluminum halides and hydrogen halides are expensive and do not readily lend themselves to recovery and reutilization in the process.

The prior art also teaches the isomerization of selected isoparaffins to other isoparaffins in the presence of hydrogen fluoride and concentrated sulfuric acid. These latter processes have the objection of being limited to the isomerization of one iso-compound to another of similar structure.

Prior to the present invention mention has been made in the literature of the isomerization effect of sulfuric acid in alkylation reactions. In all of these previous investigations the isomerization noted was the isomerization of one branched chain compound to another of more or less branched nature. In all of these earlier investigations the sulfuric acid employed as the catalytic agent was utilized at relatively low temperatures. However, isomerization of normal paraffins to the corresponding isoparaffins in the presence of sulfuric acid was heretofore unreported.

In the present invention normal paraffins are isomerized to isoparaffins with concentrated sulfuric acid as the catalyst at temperatures substantially above that employed heretofore in the isomerization of isoparaffins to more or less branched chain hydrocarbons. In its broadest aspects the invention contemplates the isomerization of normally gaseous or normally liquid normal paraffins to the corresponding isoparaffins employing concentrated sulfuric acid at temperatures in the range from about 300° F. to about

2

500° F. The invention also contemplates the isomerization of mixtures of normal paraffins occurring in the gasoline boiling ranges. One specific feature of the present invention is the isomerization of normal paraffins to isoparaffins and the alkylation of the isomerized product with olefins utilizing as the catalyst for the alkylation reaction the catalyst withdrawn from the isomerization reaction.

10 When carrying on the isomerization reaction of the present invention, the normal paraffin is contacted with concentrated sulfuric acid of a strength between 90 and 100 per cent H₂SO₄. It is preferable that the hydrocarbon be in the vapor phase when it is brought into contact with the sulfuric acid, but liquid phase may also be employed. When the hydrocarbon is in the liquid phase during the contacting step it is necessary that super atmospheric pressure be employed to maintain the hydrocarbon in liquid form at the temperatures specified.

15 In isomerizing normal paraffins to isoparaffins in the presence of concentrated sulfuric acid, the amount of acid contacted with the hydrocarbon should be at least equal to the volume of hydrocarbon charged. In general, however, it is preferred to employ an excess of hot sulfuric acid. The preferred ratios of hot sulfuric acid to hydrocarbon charge will range from about 2:1 to about 20 5:1.

25 Since hot sulfuric acid is a powerful oxidizing agent, it is preferred to employ relatively short contact times between the hot acid catalyst and the hydrocarbons. As stated above, it is preferred that the hydrocarbon contacted with the sulfuric acid be in the vapor phase, and under such conditions contact times of less than 15 minutes, and usually less than one minute, are most satisfactory. When the hydrocarbon is maintained in a liquid phase, contact times of up to 60 minutes between the sulfuric acid catalyst and the hydrocarbon may be used.

30 Since hot sulfuric acid is corrosive toward steel and steel alloys, it is desirable to inhibit hot sulfuric acid against steel and steel alloys by introducing and maintaining in the hot acid catalyst an inhibitor of corrosion. It is well known in the pickling industry when using sulfuric acid as a pickling agent to utilize inhibitors of corrosion, 35 and similar inhibitors may be used in the practice of the present invention.

40 When it is undesirable to use corrosion inhibitors as a precaution against destruction of metallic equipment, ceramic reactors and handling lines and other auxiliary equipment may be uti- 45 50 55

lized. Construction of such equipment does not present any particular problems.

The present invention will be better understood by reference to the drawings in which:

Figure 1 is a flow diagram of one embodiment of the present invention utilizing hot sulfuric acid as the catalyst;

Figure 2 is a flow diagram of another embodiment for practicing the present invention in which the product and the catalyst from the isomerization stage are cooled and then charged to an alkylation stage wherein olefins are alkylated with the isomerized product; and

Figure 3 is a flow diagram of still another embodiment in which the product and the catalyst from the isomerization stage are cooled, the isomerized product and olefins being charged directly to an alkylation reactor with recycling of a portion of the acid catalyst from the alkylation reactor back to the isomerization reactor.

In the several embodiments described with reference to the drawings, it will be assumed for purposes of illustration that normal butane is being isomerized to isobutane in the presence of hot sulfuric acid of about 97 per cent concentration at 450° F. It will also be assumed for the purpose of illustration that the normal butane is maintained in the vapor phase during the isomerization reaction.

Referring now to the drawings and specifically to Figure 1, numeral 11 illustrates a charge tank containing normal butane. Normal butane is withdrawn from tank 11 by pump 12 located in line 13 and passes through vaporizer 14 where the hydrocarbon is completely vaporized. The vaporized hydrocarbons are injected through distribution means 15 into isomerization reactor 16 wherein the vaporized hydrocarbons are intimately contacted with hot sulfuric acid descending therein and introduced by way of line 17.

The hot sulfuric acid discharged into the upper portion of isomerization reactor 16 flows downwardly therein and contacts the upflowing vaporized hydrocarbon. It is understood that isomerization reactor 16 may be a packed tower, a tower equipped with bell caps or any suitable contacting means whereby intimate contact between the vaporized normal butane and the hot sulfuric acid may be effected.

Isomerized product leaves isomerization reactor 16 by way of line 18, passes through cooler 19, wherein the product and any acid carried over with the product is cooled and liquefied, and discharges into settler 20 wherein sufficient residence time is provided for separation between the hydrocarbon and acid phases. Line 21 connects to settler 20 for removal of any SO₂ resulting from decomposition of the sulfuric acid catalyst in isomerization reactor 16.

The acid separated from the hydrocarbon phase in settler 20 discharges therefrom by way of line 22 and recycles thereby back to isomerization reactor 16. Between settler 20 and isomerization reactor 16, heat must be introduced to the withdrawn acid and this is effected by providing acid heater 23. The withdrawn acid from settler 20 is admixed with acid discharged from reactor 16 by way of line 24 and passes through coil 25 located in acid heater 23 and ultimately discharges, as described before, by way of line 17 into reactor 16.

Since, for best results, it is necessary to maintain the acid strength between 90 per cent and 100 per cent of H₂SO₄, a portion of the acid discharged from settler 20 by way of line 22 is with-

drawn from the system for further treatment as desired by opening valve 26 located in line 27. When acid is withdrawn from the system, it will be necessary to introduce a like amount of fresh acid to maintain the acid catalyst at maximum efficiency. Provision is therefore made for introduction of fresh strong acid by opening valve 28 located in line 29 connecting line 22 with an acid supply source not shown.

Since the isomerized hydrocarbon product separated from the acid in settler 20 may still contain residual acidity, provision is made for removal of acid bodies by washing the hydrocarbon with an alkaline reagent. Therefore the hydrocarbon phase from settler 20 discharges therefrom by line 30, an alkaline reagent is added thereto by line 31 and these components pass into mixer 32. The mixture of alkaline reagent and hydrocarbon discharges from mixer 32 by way of line 33 into second settler 34, which is of sufficient capacity to provide separation by gravity between the hydrocarbon and alkaline reagent phases. The isomerized product is removed from settler 34 by way of line 35 and then may be submitted to distillation for recovery of the isobutane or may be used as such, or further handled as refining practices may dictate.

The alkaline reagent phase separated from the hydrocarbon phase in settler 34 is recycled by way of lines 36 and pump 37 to contact additional quantities of isomerized product in line 39.

In order to maintain the strength of the alkaline reagent at an optimum point for removal of acidic materials, it will be necessary from time to time to withdraw a quantity of the alkaline reagent by opening valve 38 in line 39. Under these circumstances it will be necessary to introduce an equivalent amount of fresh alkaline reagent by opening valve 40 in line 31.

With respect to the embodiment shown in Figure 2, a normal butane feed in charge tank 50 is introduced by way of line 51, pump 52, and line 53, vaporizer 54 and distributor means 55 into isomerization reactor 56. As described with relation to the embodiment of Figure 1, isomerization reactor 56 may be a packed tower, a tower equipped with bell cap plates or any equivalent contacting means whereby contact between vapors and liquids is effected. The vaporized hydrocarbons pass upwardly through isomerization reactor 56 and are contacted with down-flowing hot sulfuric acid introduced thereto by way of line 57; the hydrocarbons and hot sulfuric acid remain in contact for a time sufficient to allow conversion of the normal butane to isobutane. The hydrocarbons pass upwardly and out of isomerization reactor 56 by way of line 58, are cooled and liquefied on passage through cooler 59 and are discharged into settler 60, which is provided with sufficient capacity to allow separation by gravity of hydrocarbons from entrained catalyst carried over therewith. Settler 60 is provided with line 61 to lead off any SO₂ resulting from decomposition of the sulfuric acid at the high temperatures employed in reactor 56.

The acid separated from the hydrocarbons in settler 60 discharges therefrom by way of line 62 and recycles to isomerization reactor 56 by way of line 63 and coil 64 located in acid heater 65, and line 57, as has been described before. The acid withdrawn from isomerization reactor 56 also discharges into line 63 by line 66 for passage through coil 64 for maintenance of temperature in isomerization reactor 56 and for reutilization in the process.

A branch line 67 equipped with valve 68 connects line 66 with line 62 to allow utilization of a portion of the acid withdrawn from isomerization reactor 56 as a catalyst in alkylation of the isomerized product, as will be described herein-after. Line 63 is equipped with a valve 69 for regulation of flow of acid from settler 60 to reactor 56.

The acid discharged into line 62 by way of lines 66 and 67 from isomerization reactor 56 may be routed to alkylation reactor 70 through line 71 by opening valve 72 located therein.

The isomerized product separated from the acid carried over therewith in settler 60 discharges therefrom by way of line 73 and is introduced in admixture with an alkaline reagent injected into line 73 by line 74 into mixer 75 where the alkaline reagent and hydrocarbon phases are intimately contacted for removal of residual acidic material resulting from the contact of the hydrocarbon with the hot sulfuric acid catalyst in reactor 56. The mixture of alkaline reagent and hydrocarbon discharges from mixer 75 by way of line 76 into a second settler 77 wherein provision is made for separation between isomerized hydrocarbon product and the alkaline reagent.

The separated alkaline reagent discharges from settler 77 by way of line 78 and may be recycled therefrom by pump 79 to line 74 for admixture in line 73 with additional quantities of isomerized hydrocarbon product.

Provision is made for withdrawal from time to time of amounts of alkaline reagent by opening valve 80 located in branch line 81. When alkaline reagent is withdrawn from the system by line 81, it will be necessary to introduce an equivalent amount of fresh alkaline reagent by opening valve 82 located in line 74.

The hydrocarbon separated from the alkaline reagent in settler 77 discharges therefrom by way of line 83 and is introduced thereby into separator 84, which, for purposes of illustration, may be a distillation tower. In separator 84 provision is made for separation of isobutane from unreacted normal butane. This is conveniently done by adjustment of temperature and pressure conditions by heating means 85 whereby a fraction consisting essentially of isobutane is removed overhead through line 86 for handling as will be described further. The unreacted normal butane discharges from separator 84 by way of line 53 for re-introduction into isomerization reactor 56 along with fresh feed from tank 50.

The isobutane taken overhead from separator 84 through line 86 is admixed with olefins introduced therein by way of line 87 and the mixture is discharged into line 71 carrying sulfuric acid from isomerization reactor 56 and settler 60. Prior to contact between the mixture of olefins and isobutane with the sulfuric acid, the acid is passed through cooler 88 whereby its temperature is reduced to optimum alkylation temperatures.

The cooled mixture of olefins, isobutane, and acid discharges by way of line 71 into alkylation reactor 70 wherein temperature, pressure and other conditions are maintained suitable for alkylation of the isobutane with the olefins.

The alkylation stage in the present invention is conventional to the alkylation art and details of its operation will not be gone into herein.

The effluent from the alkylation reactor containing alkylate, unreacted hydrocarbon, and entrained acid catalyst discharges therefrom by way

of line 89 into third settler 90 wherein a separation is made between the hydrocarbon and acid phases. Provision is made for withdrawing acid from settler 90 by way of line 91 and recycling of a portion of the withdrawn acid to line 71 by opening valve 92 located in line 91. Since it will be necessary to maintain the strength of acid used in isomerization reactor 56 and in alkylation reactor 70 at an optimum point for isomerization and alkylation, respectively, it will be necessary to withdraw continuously from the system an amount of spent acid and to introduce continuously an equivalent amount of make-up acid. The spent acid may be discharged from the system by opening valve 93 located in line 94 and make-up acid may be introduced into the system by opening valve 95 located in line 96 connecting line 62 to an acid supply source not shown.

In some instances it may be desirable to introduce make-up acid into the system immediately ahead of alkylation reactor 70 instead of into the acid recycled to isomerization reactor 56. In those particular instances make-up acid may be introduced into the system from a source not shown by opening valve 99 in line 100 which connects into line 71. It is understood, of course, that when make-up acid is introduced into line 71, rather than into line 62, it will be necessary to withdraw used acid from the process by opening valve 101 in line 102. Likewise, the acid separated in settler 90 from the hydrocarbon containing alkylated product will in turn be recycled to isomerization reactor 56 by opening valve 103 in line 104.

As conventional in the alkylation art, a portion of the acid emulsion discharged from the bottom of alkylation reactor 90 may be recycled to the system through line 97 and valve 98 located therein. It will be apparent from the foregoing embodiment that it is possible to employ the catalyst from the isomerization reactor for alkylation of the isomerized product. It will be further apparent that such a system, wherein a cheap reagent like sulfuric acid is utilized, embodies a considerable economic advantage over the conventional art.

With reference to the third embodiment of the present invention shown in Figure 3, a normal butane fraction from natural gasoline or any other petroleum source is introduced into the system from tank 110 by way of lines 111, 112 and pump 113 located therein. The normal butane passing through line 112 is vaporized in vaporizer 114 and is introduced through distributing means 115 into isomerization reactor 116. In isomerization reactor 116 the vaporized hydrocarbons flow upwardly therein and contact down-flowing hot concentrated sulfuric acid introduced into the upper portion of isomerization reactor 116 by way of line 117. Isomerization reactor 116 is similar to the isomerization reactors described with respect to Figures 1 and 2.

In isomerization reactor 116 temperature and other conditions are adjusted for conversion of the normal butane to the isobutane as described hereinbefore.

The product from isomerization reactor 116, consisting of isobutane and unreacted normal butane, discharges therefrom by way of line 118 and passes through cooler 119 which reduces the temperature of the hydrocarbon mixture and any entrained acid catalyst to a temperature optimum for alkylation of the isobutane with olefin 75 in the presence of sulfuric acid. This temper-

ature will generally be in the range of about 35° to 70° F. The cooled reacted hydrocarbon mixture containing entrained acid discharges by way of line 118, in admixture with olefins introduced by way of line 120 and acid injected by way of line 121, into alkylation reactor 122 wherein alkylation between the olefins and isoparaffins is effected as will be described further.

Hot acid introduced into isomerization reactor 116 by way of line 117 flows downwardly therein contacting the up-flowing vaporized hydrocarbons, introduced through distributing means 115. The hot acid flows out of reactor 116 by way of line 123 and at least a part of this acid discharges into line 124, which connects to heating coil 125 located in acid heater 126, wherein the temperature of the acid discharged from the isomerization reactor and later stages of the process is adjusted for optimum isomerization of the normal butane to isobutane.

Valve 148 is provided in line 123 for regulating the flow of discharged acid from isomerization reactor 116 by way of line 123. The reason for providing valve 148 is to allow circulation of a portion of the discharged acid to the alkylation reactor system through line 121. This is accomplished by opening valve 121 located in line 121 so that the hot acid may pass through cooler 128 for reduction of temperature of the hot acid to the proper alkylation temperature whereby the acid then admixes with the isomerized product in line 118 as has been previously described.

The mixture of isobutane, normal butane, olefins and acid discharges into alkylation reactor 122. The conditions maintained in alkylation reactor 122 are conventional in the alkylation art and will not be described further herein. It is sufficient to say that best conditions selected to give optimum alkylation between the isobutane and the olefins are maintained therein.

Acid catalyst in an emulsified state with hydrocarbons is withdrawn from alkylation reactor 122 by way of line 131 for recycling to reactor 122 through lines 132 and 121 connecting to line 118. From alkylation reactor 122 a mixture of alkylate, unreacted hydrocarbons and entrained acid is discharged by way of line 129 into settler 130.

In settler 130 sufficient residence time is allowed for gravity separation between the hydrocarbon and acid phases. After separation is accomplished, the acid is withdrawn from settler 130 by way of line 133 which connects to line 132 and which allows recycling of the acid to the alkylation reactor. From time to time it will be necessary to withdraw from the system a portion of the acid discharged from settler 130 to maintain the acid in the isomerization reactor and in the alkylation reactor at a strength optimum for the reactions. In these instances an amount of the spent acid is withdrawn from the system by opening valve 134.

When spent acid is discharged from the system it will be necessary to add an equivalent amount of make-up acid for maintenance of optimum acid strength. This is accomplished by opening valve 135 located in line 136 connecting to line 124.

Similar to the embodiment described with relation to Figure 1, it is within the scope of the present invention to introduce make-up acid into the system so that the fresh acid contacts the isoparaffin and olefins in alkylation reactor 122. In this particular instance the make-up acid will be introduced into the system by opening valve 75

144 in line 145 connecting to a source of acid storage not shown. Similar to the embodiment of Figure 1 the spent acid will be withdrawn from the acid stream recycling to the isomerization reactor 116. The acid may be discharged from the system by opening valve 146 in line 147.

In some instances it may be desirable to return a part of the acid utilized in the alkylation reaction to the isomerization system. Therefore, provision is made for introduction of the acid withdrawn from settler 130 by line 133 into isomerization reactor by opening valve 137 located in line 124, which connects to isomerization reactor 116 by way of heating coil 125 and line 117. The presence of a small quantity of alkylation acid may be beneficial in the isomerization reaction, since the alkylation acid contains small quantities of the alkyl sulfates. It has been observed, in isomerization of paraffin hydrocarbons with sulfuric acid, that the acid becomes colored on use and the theory has been advanced that the isomerization proceeds through the formation of the intermediate olefin. This would suggest the formation of alkyl sulfates. Therefore, it is within the scope of this invention to add extraneous alkyl sulfates to the isomerization acid.

The hydrocarbon phase separated from the acid in settler 130 is withdrawn therefrom by line 138, which connects to separator 139. It will be understood, of course, that acidic bodies remaining in the hydrocarbon phase may be removed by treatment with an alkaline reagent. For purposes of illustration separator 139 will be considered to be one or more distillation zones. In separator 139 temperature and pressure conditions of the hydrocarbon introduced thereto by line 138 are adjusted by heating means 140 to allow separation of an isoparaffin fraction, a normal butane fraction, and an alkylate fraction.

The isoparaffin fraction, in general, will comprise a minor portion of the stream which was introduced into separator 139 by way of line 138. Since most of the isobutane resulting from isomerization of the normal butane in isomerization reactor 116 will have been consumed in alkylation reactor 122, the remaining isobutane fraction will discharge from separator 139 by way of line 141 and may be recycled to the alkylation reactor or may be further used as desired. The unreacted normal butane discharged with isobutane from isomerization reactor 116 will be recovered by line 142 for recycling to the isomerization reactor. Line 142 connects into line 112 whereby the feed is introduced into isomerization reactor 116.

Alkylate, suitable for inclusion in 100 octane number aviation fuels, is withdrawn from separator 139 by way of line 143 for further treatment and handling. The alkylate withdrawn by way of line 143 may be distilled for separation of light and heavy alkylates and caustic washed prior to introduction of light blending agents and tetra-ethyl lead.

While the present invention has been described and illustrated by the isomerization of normal butane and the alkylation of the resulting isobutane, it is to be clearly understood that other normal paraffins, such as normal pentane, normal heptane, normal hexane and the like, may comprise the charge stock of the present process.

The nature and objects of the present invention having been completely illustrated and described, what I wish to claim as new and useful and to secure by Letters Patent is:

1. The isomerization of normal paraffins to isoparaffins comprising the steps of contacting a normal paraffin hydrocarbon with sulfuric acid maintained at a temperature in the range of 300° to 500° F. to cause the isomerization of the normal paraffin hydrocarbon and subsequently separating the resulting isomerized hydrocarbon.

2. A process in accordance with claim 1 in which the normal paraffin hydrocarbon is maintained in the vapor phase.

3. A process for converting a normal paraffin hydrocarbon to an isoparaffin hydrocarbon which comprises the steps of contacting a normal paraffin hydrocarbon in the vapor phase with sulfuric acid at a temperature of between 300° and 500° F. in an isomerization zone, removing an effluent including an acid phase and the hydrocarbon phase from the isomerization zone, cooling the effluent and separating it into a hydrocarbon phase and an acid phase, heating the separated acid phase and recycling the reheated acid to the isomerization stage and removing acidic constituents from the hydrocarbon phase.

4. A process in accordance with claim 3 in which the paraffin hydrocarbon is normal butane.

5. A process in accordance with claim 3 in which the normal paraffin hydrocarbon is normal pentane.

6. In the production of high octane number fuels the steps of isomerizing a normal paraffin hydrocarbon by contacting it in vapor phase with

sulfuric acid at a temperature of between 300° and 500° F., separating isomerized hydrocarbon product from the hot acid catalyst, cooling the hydrocarbon product and adding olefins thereto, cooling the acid catalyst and mixing it with the hydrocarbon phase containing olefins and maintaining the mixture under conditions to cause alkylation of the olefins and subsequently recovering an alkylate of high octane number.

10 7. A process in accordance with claim 6 in which the normal paraffin hydrocarbon is normal butane and the added olefins are butylenes.

8. A method for producing alkylate which comprises contacting a normal paraffin in vapor phase with sulfuric acid in an isomerization zone at a

15 temperature of between 300° and 500° F. to cause isomerization of the normal paraffin, separating the resulting isomerized hydrocarbon product from the acid, mixing olefins with the hydrocarbon product, cooling the acid and adding it thereto and maintaining the mixture under conditions to cause alkylation of hydrocarbons present therein, separating a hydrocarbon phase containing alkylate from an acid phase, recovering isoparaffins, normal paraffins and alkylate from the hydrocarbon phase and recycling at least a portion

20 of the acid phase to the isomerization zone.

25 9. A process in accordance with claim 8 in which the normal paraffin is vaporized normal butane.

30 THOMAS B. McCULLOCH.
